US00D985606S

(12) **United States Design Patent** (10) **Patent No.:** **US D985,606 S**
(45) **Date of Patent:** **** May 9, 2023**

(54) **DISPLAY SCREEN OR PORTION THEREOF
WITH GRAPHICAL USER INTERFACE**

(71) Applicant: **Waymo LLC**, Mountain View, CA (US)

(72) Inventors: **Maria Moon**, Mountain View, CA (US); **Matthew Corey Hall**, San Jose, CA (US); **Peter Crandall**, San Jose, CA (US)

(73) Assignee: **Waymo LLC**, Mountain View, CA (US)

(**) Term: **15 Years**

(21) Appl. No.: **29/804,860**

(22) Filed: **Aug. 23, 2021**

(51) LOC (14) Cl. **14-04**

(52) U.S. Cl.

(57) **CLAIM**

The ornamental design for a display screen or portion thereof with graphical user interface, as shown and described.

DESCRIPTION

FIG. 1 is a front view of the claimed design for a display screen or portion thereof with graphical user interface; FIG. 2 is a front view of an alternative embodiment of the claimed design for a display screen or portion thereof with graphical user interface; and, FIG. 3 is a front view of an alternative embodiment of the claimed design for a display screen or portion thereof with graphical user interface.

The outer rectangle in each drawing shows a display screen, the broken lines showing the display screen or portion thereof with graphical user interface depict environmental structure and form no part of the claimed design.

1 Claim, 3 Drawing Sheets
